[57] CLAIM

The ornamental design for a combined automobile tail-light lens and grill, as shown and described.

DESCRIPTION

FIG. 1 is a perspective view of a combined automobile taillight lens and grill showing the new design;

FIG. 2 is a front elevation view thereof;

FIG. 3 is a top plan view thereof;

FIG. 4 is a bottom plan view thereof;

FIG. 5 is a left side elevation view thereof; and

FIG. 6 is a right side elevation view thereof.

The taillight housing is shown in broken lines in FIGS.
1, 3, 4 and 6 for illustrative purposes only.

FIG. 1
